UNITED STATES PATENT OFFICE

ELWIN GEORGE QUELLHORST, OF CLEVELAND, OHIO

ELECTRIC HAMMER

Application filed December 20, 1929. Serial No. 415,447.

This invention relates to electrical appliances and tools, and has more particular reference to an electric motor driven hammer with general utilitarian purposes.

5 Briefly, the invention has reference to a small portable electric hammer including an electric motor, a carrying handle therefor, and a mechanism barrel associated with the motor, the arrangement being such as to afford a unique, simplified and economical arrangement of parts.

10 My principal aim is to generally improve upon tools of this class by providing one which is characterized by a distinguishable arrangement of parts structurally cooperating in producing a tool which is compact and convenient in arrangement, susceptible of easy manipulation, and otherwise developed to fulfill the requirements of an implement of 15 this class in a highly satisfactory and efficient manner.

In the drawings:

Figure 1 is a top plan view of a hammer constructed in accordance with the present 20 invention.

Figure 2 is a central longitudinal sectional view through the same.

Figures 3 and 4 are cross sections on the lines 3-3 and 4-4 respectively of Figure 2. 25 Figure 5 is an enlarged fragmentary detail section on the line 5-5 of Figure 2.

Figure 6 is a section on the line 6-6 of Figure 5.

Figure 7 is a front view of one of the 30 tails.

The general assembly may well be seen in Figure 2 wherein it will be observed that the reference character 8 designates a small portable electric motor of appropriate power. 40 The motor includes a housing embodying a body section 9 having flanges 10 and 11 at its opposite ends. A cap 12 is bolted to the flange 11. Also, the inturned extremities 13 of a handle forming bail 14 are secured 45 to the same flange by the same bolt, thus mak-

ing for compactness and convenience in arrangement.

It might be stated that the handle is provided with a suitable switch of the construction shown in Figures 5 and 6. The handle 50 is hollowed out to provide recesses to accommodate the parts. One recess serves to accommodate the button which is in the nature of a plate 15 pivoted in a recess and having pin and slot connection as at 16 with a movable contact rod 17. The free end of the rod is positioned to move between the contact 55 18 in which the electric wires (not shown) are connected.

The numeral 19 designates a spring which 60 serves to hold the button 15 in the projected position seen in Figure 6. Merely pressing the button 15 in, serves to move the rod 17 between the contact 18 to close the circuit and set the motor 8 into operation.

Bolted to the flange 11 is a disc-like head plate 20 to which a spacing ring 21 is fastened. The ring serves to space the plate 20 from a similar plate 22. The plate 22 has an eccentric screw threaded socket 23 receiving 70 the screw threaded end of the cylindrical barrel 24. Interposed between the plates 20 and 22 is a gear 25 carried by the left hand end of a square shaft 26. The spindle on the left hand end of the shaft is journaled in a bearing 75 in the plate 20.

The motor shaft is provided with pinion 27 in mesh with the gear 25 rotating the shaft 26. The right hand end of the barrel is formed with a reduced conical guide 28. The 80 stem portion 29 of a plunger is slidable in this guide and projectable beyond the right hand end thereof. The plunger includes a body portion 29 slidable in the barrel and 85 having a central socket 30 receiving the adjacent end of the square shaft 26. This forms a slidable joint for the plunger. Thus the plunger is rotated and in addition is allowed to slide back and forth in a reciprocatory 90

manner, the stroke being governed by the means shown.

For instance, the portion 31 of the plunger is provided with a spiral thread 32 receiving the end portion 33 of a guiding and releasing screw. It will be noted that the adjacent ends of the threads are spaced apart longitudinally to permit the desired reciprocatory action of the plunger. The plunger is actuated by a coiled spring 34 arranged in the barrel and bearing at one end against the body 29 and at its opposite end against an adjustable follower ring 35 in the left hand end portion of the barrel.

In operation, it is obvious when the motor is set in motion by closing the switch, the gearing 25 and 27 will serve to rotate shaft 26. This will in turn rotate the plunger, the plunger being held by the spring in a position to maintain the thread 32 in contact with the relatively stationary release and guide screw 33. Thus, as the plunger turns around, it will be fed in the compressed spring, and at certain moments in the period of rotation, as the end of the thread passes screw 33, the spring will quickly snap the plunger outwardly forcing the tool stem 29' against the work in a reciprocatory manner.

From the foregoing description and drawings it will be seen that I have evolved and produced a simple and practical arrangement of parts structurally co-related in forming a novel electrically driven hammer, the same being portable, powerful, easy to manipulate, easy to repair, and otherwise susceptible of accomplishing the desired aim in a practical manner.

Persons skilled in the art to which the invention relates will be able to obtain a clear understanding of the same after considering the description in connection with the drawings. Therefore, a more lengthy description is regarded as unnecessary.

Minor changes in shape, size, and rearrangement of details coming within the field of invention claimed may be resorted to in actual practice if desired.

I claim:

In an electric hammer of the class described, a cylindrical barrel having one end formed with a conical guide and having the opposite end open and internally and externally screw threaded, a bearing and gearing assembly detachably mounted on the externally screw threaded portion of said barrel, a follower ring adjustably mounted on the interior of the barrel and engaged with the internal screw threads, a shaft mounted for rotation in the bearings and operatively connected with the gearing, a rotatable and reciprocatory plunger in the opposite end portion of the barrel including a reduced stem slidable through said conical guide, and also including a body portion having a socket receiving slidably, the adjacent end of said

shaft, an intermediate portion integrally formed with the plunger and reduced stem, a spiral thread formed on said intermediate portion, said thread having its ends longitudinally spaced, a guide and releasing screw 70 mounted in said barrel, and cooperating with the spiral threads for permitting intermittent reciprocation of the plunger, and a coil spring bearing at one end against the follower plate and at the opposite end against the body portion of the plunger.

In testimony whereof I affix my signature.
ELWIN GEORGE QUELLHORST. 75
